UNITED STATES PATENT OFFICE.

LESLIE R. N. CARVALHO, OF TOLEDO, OHIO, ASSIGNEE TO THE CLOSURE SERVICE COMPANY, OF TOLEDO, OHIO, A CORPORATION OF OHIO.

CLOSURE DEVICE.

Application filed October 3, 1925. Serial No. 60,154.

My invention relates to closures for containers such as tumblers, jars or other similar containers, embodying certain features of and being in the nature of an improvement 5 over the structures shown and described in my co-pending application, Serial Number 685,530.

More specifically, my invention relates to bottle closures of a type consisting of a top 10 portion and a depending flange portion, the latter being formed with a peripheral bead near its lower extremity and having a cut-away portion in the said bead for the introduction of a suitable prying implement. A 15 score line has generally been disposed so as to cross this cut-away portion or slot.

It has been found in practice that when a 20 cap has been scored so as to have the score line crossing or bordering the cut-away portion or slot in the flange, much difficulty has been experienced in the sealing operation from tears occurring at the cut-away portion and extending along the scoring line. Such tears arising during the sealing operation, 25 are very objectionable. The segregated portions are weakened and elongated by virtue of the aforesaid tears and are unable to be properly crimped on the head of the bottle neck. Furthermore, the cap is obviously lacking in strength from such a construction.

An object of my invention is to produce practical and simple means for obviating the above disadvantages in a simple and practical manner.

A further object of my invention is to provide means whereby a cap or closure is kept from tearing during the sealing operation thereof.

Other objects of the invention will appear hereinafter.

In the accompanying drawings:

Figure 1 is a fragmentary side elevation, partly in section, of a bottle fitted with a closure, constructed in accordance with my invention.

Figure 2 is a horizontal section taken along line II-II on Figure 1.

Figure 3 is a fragmentary elevation of a 50 bottle and my improved closure device, and showing the use of a suitable implement to separate the removable sealing strip.

Figure 4 is a fragmentary elevation, partly 55 in section, of my improved device, adapted to another form of bottle.

Referring now to the drawings for a description in detail of my invention illustrated therein, there will be seen a closure or cap 5 comprising a top portion 6, and a depending flange or skirt 7. There is formed in the 60 depending flange 7, a little above the margin of said flange, a rib 8 extending circumferentially of the flange. There is further formed in the depending flange 7, a slot 10 65 extending upward from the lower edge of the flange to or through the rib 8, permitting the insertion of a suitable prying implement 12 under the aforesaid rib 8. The lower margin of the depending flange or skirt 7 is formed to extend downwardly a little past 70 the rim 13 of the bottle over which it is to fit and provide a sufficient edge to allow crimping the cap to the bottle finish. Above the said rib 8 and the said slot 10, a circumferential score line 11 for separating the said 75 flange into two parts is formed in the aforesaid flange 7. A gasket 14 made of cork or other suitable material, is disposed within the cover 5. Figure 4, it will be noted, discloses a similar construction, as above described, 80 but applies the principles of my invention to a bottle of narrower neck. In the use of my invention, the closure 5, with the gasket 14 inserted therein, is placed upon the bottle it is to close, and the lower margin 9 is bent 85 under the rim 13 of the bottle neck, thereby crimping the closure of said bottle.

I contemplate, in my invention, to dispose the score line 11 across the flange 7 a little above the rib 8 and the slot 10 therein. With 90 this arrangement, accidental tearing of the flange at the slot during the above sealing operation, is avoided.

For opening the bottle, a suitable implement 12 is inserted through the slot 10 under 95 the rib 8, and pressed upwardly, causing a tear of the rib portion of the skirt along the score line 11. The amount 15 so torn, affords a gripping means for further tearing by hand and thereby completely removing the 100 removable strip or sealing band below the score line, leaving a complementary cover 16 for temporary use during the dispensation of the contents of the container.

Modifications of the above may be made 105 within the spirit and scope of my invention.

What I claim is:

1. A receptacle closure having a marginal portion adapted to overlie an exterior portion of a receptacle, said marginal portion 110

being formed near its lower extremity with a transverse rib, and an upwardly extending slot having its upper boundary in said rib furnishing an aperture therein for the insertion of a prying implement, said marginal flange being further formed with a peripheral score line spaced apart from said slot.

2. A bottle closure including a top portion and a depending flange portion, the said flange portion being formed with a peripheral bead and having a cut-away portion in said bead for the immediate insertion of an opening implement, said flange portion being also provided with a peripheral score line spaced apart from said peripheral bead and cut-away portion.

3. A bottle closure comprising a top and a skirt portion, said skirt portion having its lower marginal portion provided with sealing and opening means, including a marginal extremity for crimping the said closure to a bottle, and a peripheral score line spaced above a peripheral bead formed in the said skirt, said bead being provided with an aperture therein for the insertion of an opening implement, said aperture being spaced from the score line.

4. A receptacle closure comprising a top cover portion and a marginal flange, said flange formed with a score line extending lengthwise thereof and also formed with a slot extending upwardly from the lower edge of the flange and terminating at a point spaced below the score line.

5. A receptacle closure comprising a top cover portion and a marginal flange, said flange formed with a score line extending lengthwise thereof and also formed with a

slot extending upwardly from the lower edge 40 of the flange and terminating at a point spaced below the score line, said flange also formed with a circumferential bead beneath the score line and into which said slot extends.

6. A sheet metal closure comprising a top portion and an integral depending flange, said flange being formed with a bead extending circumferentially thereof and also formed with a circumferential score line 50 above the bead, said flange being formed with a slot extending upward from the lower edge of the flange into the bead and having its upper end spaced below the score line.

7. The combination of a container and a closure cap therefor, said cap comprising a top cover portion and a depending flange, said flange being formed with a bead extending circumferentially of the container and providing an annular space between the 60 inner surface of the bead and the surface of the container, said bead being cut away at one point in the periphery thereof to provide an opening permitting the insertion of a tool between the bead and the container, 65 said flange being formed with a circumferential score line above the bead and spaced from said opening, said opening being extended downward to the lower edge of the flange, said container being formed 70 with an annular shoulder, the lower edge of the flange being inturned beneath said shoulder, whereby the cap is secured to the container.

Signed at Toledo, in the county of Lucas 75 and State of Ohio, this 29th day of September, 1925.

LESLIE R. N. CARVALHO.
